UNITED STATES PATENT OFFICE.

CLINTON E. MARSHALL, OF BROOKLYN, NEW YORK.

FOUNTAIN PEN.

Application filed March 10, 1926. Serial No. 93,596.

This invention relates to fountain pens and particularly to an improved lever construction and mounting for pens of the class under consideration employing compressible walls 5 or sacks compressed by said lever through a bar positioned between the lever and the sack; and the object of the invention is to provide means for pivotally mounting a lever in connection with the pen body and tensional 10 means engaging said lever for retaining the same in closed or inoperative position and out of operative connection with the bar employed; a further object being to provide the bore of the pen body with an annular groove 15 or recess in which a coil spring is adapted to be mounted for engagement with a notch in said lever for retaining the same in position and against accidental displacement; and with these and other objects in view, the invention 20 consists in a device of the class and for the purpose specified which is simple in construction, efficient in use and which is constructed as hereinafter described and claimed.

25 The invention is fully disclosed in the following specification, of which the accompanying drawing forms a part, in which the separate parts of my improvement are designated by suitable reference characters in 30 each of the views, and in which:—

Fig. 1 is a partial, longitudinal, sectional view through a pen body illustrating my improved lever construction mounted in connection therewith.

35 Fig. 2 is a plan view of a part of the construction shown in Fig. 1.

Fig. 3 is a section on the line 3—3 of Fig. 1 and on an enlarged scale; and

40 Fig. 4 is a perspective detail view of the lever which I employ.

In Fig. 1 of the drawing, I have indicated at 10 the barrel of a fountain pen which is closed at one end as seen at 11, and the pen point tip portion 12 is mounted in connection 45 with the open end thereof and carries the usual flexible or compressible well sack 13 which extends into the barrel 10 of the pen. At 14, I have indicated a bar which may be of any conventional form, which lies upon 50 one face of and extends longitudinally of the sack 13. In the construction shown, the bar 14 is of channel formation in cross section as clearly seen in Fig. 3 of the drawing.

In the barrel or body 10 of the pen substantially centrally thereof is an elongated aperture 15 in which is mounted a lever 16 piv-

oted to a split wall ring 17. The ring is retained in position by engagement with an annular groove 18 in the bore of the body 10. The lever 16 is of channel formation in cross section, the channel being directed inwardly with reference to the bore of the body 10 when the lever is in use. One end 19 of the channel is reduced and the side flanges rounded for engagement with the bar 14 in the operation of compressing the sack 13, while at the other end of said lever the flanges are cut backwardly to form notches 20 therein and to provide a projecting lip or finger piece 21 whereby the operation of the lever is facilitated. That part of the barrel or body 10 adjacent the finger piece 21 is recessed as seen at 22 to permit of the insertion of the nail of a finger beneath the finger piece 21 to permit the lever to be raised into vertical or substantially vertical position in the depression of the bar 14 to compress the sack 13.

Adjacent the recess 22 in the body 10, the bore thereof is provided with a comparatively wide annular recess 23 in which is mounted 80 a light coil spring 24 in such position and relation with the lever 16 as to engage the notches 20 in the side flanges of said lever to retain the lever in the position shown in Fig. 1 of the drawing against accidental displacement, and further to support said lever in parallel relation with reference to the outer face of the barrel or body 10 of the pen, and with the ends 19 of the lever out of engagement with the bar 14 as clearly seen in Fig. 1 85 of the drawing.

It will be understood that my invention is not limited to the use of a bar of any specific form and construction nor am I necessarily limited to the specific means herein shown 90 and described for retaining the lever in position, and various other changes in and modifications of the construction herein shown and described may be made within the scope of the appended claims without departing from 100 the spirit of my invention or sacrificing its advantages.

Having fully described my invention, what I claim as new and desire to secure by Letters Patent, is:—

1. In a pen of the class described, a lever pivotally mounted in the body of the pen, a finger piece at one end of the lever whereby the other end of said lever may be moved into the body of the pen, and means adjacent 110 the finger piece end of the lever and cooperating therewith for retaining said lever in inop-

erative position and in parallel relation with reference to the wall of said pen body, said means comprising a coil spring mounted in the bore of said pen body and cooperating 5 with a notched portion on said lever.

2. In a pen employing a pen body, a compressible well within said body and a bar extending longitudinally of said well, a lever pivotally mounted in an aperture in the body 10 of the pen, said lever when in horizontal position being out of engagement with said bar, means for retaining said lever in such position against displacement, and said means comprising a spiral spring mounted in an annular groove in the bore of the pen body and adapted to engage a notched portion on 15 said lever.

3. In a pen employing a pen body, a compressible well within said body and a bar extending longitudinally of said well, a lever pivotally mounted in an aperture in the body 20 of the pen, said lever when in horizontal position being out of engagement with said bar, means for retaining said lever in such position against displacement, said means comprising a spiral spring mounted in an annular groove in the bore of the pen body and adapted to engage a notched portion on 25 said lever and the notched end portion of 30 the lever being provided with a finger piece.

4. In a fountain pen of the class described, the bore of the body of which is provided with

a comparatively wide annular groove, a coil spring mounted in said groove, the well of the pen body having an elongated aperture extending longitudinally thereof and opening into said annular groove, and a lever pivotally mounted in the aperture of the pen body and one end of said lever being fashioned to engage said coil spring to retain said lever in 40 parallel relation with reference to the well of the pen body.

5. In a self-filling fountain pen, a lever pivotally mounted in the body of the pen, a bar mounted in the pen and adapted to be actuated by said lever, said lever comprising an elongated strip of metal of channel formation in cross section, the side walls at one end of the lever being cut away to form a projecting finger piece, and notches in the ends of said side walls and directed toward said finger piece, the bore of the pen body having a comparatively wide annular groove adjacent the notch portion of the lever, and a comparatively 50 light coil spring adapted to be supported in said groove and to engage the notches in the end of said lever to retain said lever in horizontal position with reference to the wall of the pen body and out of engagement with 55 said bar.

In testimony that I claim the foregoing as my invention I have signed my name this 1st day of March, 1926.

CLINTON E. MARSHALL.
